ROBERT H. W. STRANG, OF BRIDGEPORT, CONNECTICUT.

INSTRUMENT FOR HOLDING APPLIANCES WHILE HEATED.

1,415,414.

Specification of Letters Patent.

Patented May 9, 1922.

Application filed March 12, 1921. Serial No. 451,848.

To all whom it may concern:

Be it known that I, ROBERT H. W. STRANG, a citizen of the United States, residing at Bridgeport, county of Fairfield, State of Connecticut, have invented an Improvement in Instruments for Holding Appliances While Heated, of which the following is a specification.

This invention relates to the preparation and adjustment of the wire arches used by 10 orthodontists in the treatment of malocclusion. An arch of this character is usually anchored at its ends by means of attaching devices or buccal tubes secured in fixed position to teeth at opposite sides of the jaw at 15 the rear of the mouth, the intermediate portions of the arch, which is composed of resilient material, engaging or being secured to the teeth to be moved so as to exert a yielding 20 pressure thereon in the desired direction. These arches must, of course, be suitably shaped to fit the requirements of the individual case, must, in many instances, have attached thereto at the proper points pins or 25 other devices for engaging the individual teeth in the required manner and must, from time to time as the treatment progresses, be changed in form and otherwise modified in accordance with the varying requirements. 30 The arch, when in operative position, must, in order to perform its intended function, be of a resilient character, but, in order to permit the necessary minor changes in configuration, it must be annealed or softened, for 35 which purpose, as well as to permit the attachment, removal or readjustment of the pins or other tooth engaging elements, it must be heated, after which operations it must be restored to its resilient condition, as 40 by tempering. During the operation of thus adjusting an arch, as well as in its original preparation, it is desirable that the general shape of the arch be retained in order that it may properly fit the mouth for which it is 45 intended without considerable adjustment or manipulation at the time of being placed in position. It is also sometimes desirable that this general form be changed to spread or 50 contract the arch without changing the relative angular positions of its ends.

The present invention has for its object to provide a device for holding such an arch during the various operations of heating, annealing, tempering, bending, or otherwise 55 adjusting the same, as well as during the attachment, removal, or replacement of the

tooth engaging pins thereon, which device will support the arch in a suitably elevated position with its intermediate portion free to be heated and to receive the necessary adjustments or other manipulations, said device holding the arch in a position closely corresponding to its position in the mouth by means of holding members which engage the ends of the arch and which are substantial 60 duplicates of the buccal tubes by which the ends of said arch are normally anchored in the mouth, said holding members being supported in such a manner as to permit the same to be relatively moved while preserving 65 their relative angular positions or approximate parallelism, so as to permit the arch to be spread or contracted without otherwise materially affecting the same.

With the foregoing and other objects in view I have devised the novel work holding device which I will now describe, reference being had to the accompanying drawings, in which:

Fig. 1 is a perspective view, on a somewhat enlarged scale, of the complete device.

Fig. 2 is a greatly enlarged vertical section of the support for one of the arch holding members, the latter being shown in elevation.

10 denotes a bar having at one end a fixed or rigid arm 11 extending substantially at right angles thereto and a rigid supporting foot 12 disposed substantially at right angles to said bar and arm. 13 denotes a slide mounted for longitudinal movement on said bar 10 and held in adjusted position thereon by a set screw 14, said slide having a rigid or integral arm 15 and a rigid or integral supporting foot 16 similar respectively to the 90 arm 11 and foot 12. The bar 10 is of non-circular cross section, being preferably flattened on its upper and lower faces, and the slide 13 is provided with a correspondingly shaped opening to receive said bar, whereby 95 said slide is held against turning on said bar with its arm 15 and foot 16 parallel respectively to the arm 11 and foot 12.

The arms 11 and 15 are provided at their forward ends with preferably integral, vertically disposed, tubular supporting members 17 by which are adjustably carried in an elevated position the members 18 for holding the ends of the arch 19. The members 18 are of tubular form and are substantially duplicates of the buccal tubes by which the ends of the arch are secured to the

anchor teeth in the mouth of the patient, said members being provided with integral supporting stems disposed substantially at right angles thereto. Each stem 20 terminates at its lower end in a ball 21 which is seated in a socket 22 formed on the inner surface of an upper end portion 23 of the corresponding supporting member 17, said end portion having an outwardly flared opening 24 to receive the stem 20, thereby permitting a universal adjustment of each holding member 18 with respect to its support 17. The balls 21 are held seated in the sockets 22 by means of followers 25 having depressions to engage said balls, said followers being forced upwardly to clamp said balls and thereby hold the members 18 in adjusted position by means of screw plungers 26 having threaded engagement with the interiors of the tubular supports 17 and provided with upwardly projecting fingers 27 which engage said followers. The followers 25 are retained against accidental escape from the tubular supports 17 by means of bushings 28, also in threaded engagement with the interiors of said supports, and having central openings through which the fingers 27 extend. The screw plungers 26 are provided with operating stems 29, preferably formed at their lower ends with transverse handle portions 30 whereby said plungers may be conveniently turned to release the members 18 for purposes of adjustment or to clamp the same in adjusted position. The stems 29 and handles 30 also constitute feet upon which the tubular supports 17 rest, said feet supporting the forward ends of the arms 11 and 15 the rear ends of which, together with the bar 10, are supported upon the feet 12 and 16.

In operation the slide 13 is adjusted upon the bar 10 into such a position as to set the holding members 18 at a distance apart corresponding substantially to the distance separating the buccal tubes in the mouth of the patient, the clamping devices for the balls 21 are released, and the ends of the arch are inserted into said holding members, which are thereby caused to assume relative positions closely corresponding to the relative positions of said buccal tubes. The clamping devices are then tightened, causing the arch to be supported in a position substantially identical with that assumed by it in the mouth of the patient. The arch while in this position may then be heated for the purpose of annealing or tempering the same, may be bent or otherwise adjusted in order to make whatever minor changes in configuration may be required, or the tooth engaging cleats, spurs or pins 31 may be soldered thereto at the required points or removed therefrom, all without materially changing the general shape of the arch or the relative positions of its ends, thereby

permitting the necessary adjustments to be accurately made, and enabling the arch to be placed in the mouth of the patient without special readjustment for that purpose. Should it be desired to spread or contract 70 the arch, this may be done without disturbing the relative angular positions of the holding members 18 by releasing the set screw 14 and moving the slide 13 along the bar 10. 75

Having thus described my invention, I claim:

1. A device of the character described comprising a pair of tubular arch holding members adapted for insertion of the ends 80 of a tooth regulating arch, and supports by which said members are adjustably carried adapted to permit said members to hold said arch in a position to permit its intermediate portion to be heated and manipulated. 85

2. A device of the character described comprising a pair of tubular arch holding members having rigid stems, supports for said members, and ball and socket joints connecting said stems and supports. 90

3. A device of the character described comprising a pair of tubular arch holding members, supports for said members, and a bar by which one of said supports is rigidly carried, the other of said supports being adjustably mounted on said bar. 95

4. A device of the character described comprising a pair of tubular arch holding members, supports for said members, and a bar to which one of said supports is fixed, the other of said supports being adjustably mounted on said bar. 100

5. A device of the character described comprising a pair of holding members, supports for said members, a bar by which said members are carried, and supporting feet carried by said bar and supports respectively upon which said device rests. 105

6. A device of the character described comprising a pair of holding members, supports for said members, a bar to which one of said supports is fixed, the other of said supports being adjustably mounted on said bar, and supporting feet carried by said supports and bar respectively upon which said device rests. 110

7. A device of the character described comprising a pair of tubular holding members, supports for said members, a bar to 120 which one of said supports is fixed, a slide adjustably mounted on said bar, and an arm on said slide by which the other of said supports is carried.

8. A device of the character described 125 comprising a pair of holding members, supports for said members, a bar to which one of said supports is fixed, a slide adjustably mounted on said bar and by which the other of said supports is carried, and supporting 130

- feet carried by said bar and slide respectively upon which said device rests.
9. A device of the character described comprising a pair of holding members, tubular supports for said members, ball and socket joints connecting said members and supports, and clamping devices for said ball and socket joints to hold said members in adjusted position on said supports, said clamping devices having operating portions constituting feet upon which said device rests.
10. A device of the character described comprising a pair of tubular holding members, supports for said members, ball and socket joints connecting said supports and members, a bar to which one of said supports is fixed, and a slide adjustably mounted on said bar and by which the other of said supports is carried.
11. A device of the character described comprising a pair of holding members, tubular supports for said members, ball and socket joints connecting said members and supports, clamping devices for said ball and socket joints to hold said members in adjusted position on said supports, a bar to which one of said supports is fixed, a slide adjustably mounted on said bar and by which the other of said supports is carried, said clamping devices having operating portions constituting supporting feet upon which said device rests, and other supporting feet for said device carried by said bar and slide respectively.
12. A device of the character described comprising a pair of tubular holding members, supports for said members, a bar having a fixed arm by which one of said supports is carried, a slide adjustably mounted on said bar, and an arm on said slide disposed substantially parallel to the arm on said bar and by which the other of said supports is carried.

13. A device of the character described comprising a pair of holding members, supports for said members, a bar having a fixed arm by which one of said supports is carried, a slide adjustably mounted on said bar, an arm on said slide disposed substantially parallel to said first named arm and by which the other of said supports is carried, and supporting feet for said device carried by said supports, bar, and slide respectively.

14. A device of the character described comprising a pair of tubular holding members, a supporting means provided with supports for said members, and universal connections between the members and the supports.

15. A device of the character described comprising a pair of tubular holding members, supports for said members, means for connecting said supports, means connecting the members to the supports and adapted to allow universal adjustment of the members thereon, and means for securing the members in adjusted position.

16. A device of the character described comprising a pair of tubular holding members, supports for said members having universal connection therewith, means for securing the members in adjusted position on said supports, supporting means connecting the supports and allowing relative adjustment of the supports, and means for securing the supports in adjusted position.

17. A device for holding tooth regulating arches comprising non-clamping holding members for the sides of the arch, supports for said members having adjustable connection therewith, and means for securing the holding members in adjusted position.

In testimony whereof I affix my signature.

ROBERT H. W. STRANG.
